UNITED STATES PATENT OFFICE.

HENRY F. SPAULDING, OF CANASTOTA, SOUTH DAKOTA.

CORN-PLANTER.

No. 800,180.

Specification of Letters Patent.

Patented Sept. 26, 1905.

Application filed May 11, 1905. Serial No. 259,949.

To all whom it may concern:

Be it known that I, HENRY F. SPAULDING, a citizen of the United States, residing at Canastota, in the county of McCook and State of 5 South Dakota, have invented a new and useful Corn-Planter, of which the following is a specification.

This invention relates to corn-planters, and especially to that class which are known as 10 "check-rowers," the object of the invention being to present a wireless check-row corn-planter which shall possess superior advantages in point of simplicity, durability, and general efficiency and in which the dropping 15 of the charges of seed shall be accomplished positively at regular predetermined intervals in a simple and effective manner.

With these and other ends in view, which 20 will readily appear as the nature of the invention is better understood, the same consists in the improved construction and novel arrangement and combination of parts which will be hereinafter fully described, and particularly pointed out in the claims.

25 In the accompanying drawings has been illustrated a simple and preferred form of the invention, it being, however, understood that no limitation is necessarily made to the precise structural details therein exhibited, but 30 that changes, alterations, and modifications to which recourse may be had within the scope of the invention and without departing from the spirit or sacrificing the efficiency of the same may be made.

35 In said drawings, Figure 1 is a top plan view of a check-row corn-planter constructed in accordance with the principles of the invention. Fig. 2 is a side elevation of the same. Figs. 3 and 4 are sectional elevations, on an enlarged 40 scale, representing, respectively, the front and rear ends of the adjustable frame in which is mounted the stake or tappet carrying chain and related parts. Fig. 5 is a rear end view of the machine. Fig. 6 is a sectional detail 45 view, enlarged, taken on the plane indicated by the line 6-6 in Fig. 2; and Fig. 7 is a perspective detail view, enlarged, of one of the stakes or tappets and its supporting link or casing.

50 Corresponding parts in the several figures are indicated throughout by similar characters of reference.

The main frame of the improved machine includes side members 11, which are suitably 55 connected with the legs of the axle-arch 2, which latter is relatively high and narrow, the

legs being bent outward at their lower ends to form spindles 3, upon which the carrying-wheels 4 are mounted for rotation. Upon the inner sides of the legs of the axle-arch are 60 secured guide members or tracks 5, consisting of channel-bars, the lower ends of which are extended below the legs of the arch to afford bearings for a vertically-movable arch member 6. Brace members 7, having horizontally-disposed portions 8, connect the side members 1 of the frame with the track members 5 at some distance below the spindles 3 of the axle. The side members 11 may be made to converge rearwardly, as shown at 9, 70 in order to support a seat 10 for the driver and operator.

The vertically movable or slidable arch member 6 serves to support a frame which includes side members 11, provided at the 75 ends thereof with upstanding portions 12, having longitudinally-extended brackets 13, provided with slots 14. The arch member 6 is pivotally connected with the side members 11 about midway of the length of the latter, 80 which will thus be nearly balanced upon its pivots. The slots 14 at the ends of the side members support longitudinally-adjustable stub-shafts 15, upon which are mounted freely-rotatable pulleys 16, provided adjacent to their 85 outer sides with peripheral offsets or recesses 17. The pulleys 16 are suitably spaced apart to accommodate between them an endless chain 18, including in its construction a number of links 19 of special construction for the 90 reception of the earth-engaging stakes 20, which serve as tappets for the purpose of operating the seed-dropping mechanism, as will be hereinafter more fully described.

The special links 19, of which any desired 95 number may be used in the chain, which latter, in fact, may be constructed exclusively of such special links 19, are equipped with sleeves or casings 21, which are approximately rectangular in cross-section to accommodate 100 the slidable stakes 20. Said sleeves or casings have been shown most clearly in Fig. 7 of the drawings, by reference to which it will be seen that the casing is provided at the four corners thereof with antifriction-rollers 22, 105 between which the stake may move freely. Each of said sleeves or casings is also provided at its front and rear edges with laterally-extending arms 23, adapted to engage the peripheries of the supporting-pulleys 16, said 110 arms being provided at the ends thereof with rollers 24 of suitable diameter to travel in the

tracks provided by the peripheral offsets 17 in said supporting-pulleys. The stakes 20, operating in the sleeves or casings 21, are provided near their upper ends with transverse pins or shafts 25, carrying rollers 26. The upper extremities of said stakes are bifurcated and are provided with transverse shafts or pins 27, which project upon the sides of the stakes and carry rollers 28, which are located in the forks 29 of said stakes. The designation "upper ends," which has been used with reference to the stakes, applies to the latter when in an upright earth-engaging position.

The side members 11 of the chain-carrying frame, which latter as a whole is designated F, are connected near their front and rear ends by arch members 30, which are substantially made of wrought-iron or other suitable material and which may be pivotally connected with the stub-axles 15, upon which the chain-supporting pulleys 16 are mounted. Said side members 11 support vertically-adjustable yokes 31, carrying a track 32, whereby the earth-engaging stakes are guided and forced into the ground, said track being located between the upper and lower leads of the endless chain 18. The track 32 includes an upper and a lower member, (designated, respectively, 33 and 34,) said upper member being horizontally disposed throughout, while the forward end of the lower member 34 is inclined upwardly, as shown at 35, to the point 36, where it merges with or is continued in the upper track member. The lower track member 34 terminates some distance in front of the upper track member 33. The front end of the track 32 is provided with a guide-flange 36', having an overhanging lip or flange 37. The two track members 33 and 34 may, if desired, be spaced apart, as by bracket members 38.

Upon the inner sides of the side members 11 of the frame F are placed channel-bars 39, affording guides for the rollers 24 at the ends of the link-arms 23, the function of said channel-bars being to keep the stake-carrying links evenly spaced above the ground and to obviate any tendency to vertical displacement. Lateral displacement of the frame F and its related parts will be prevented by the extended guiding means for the frame-carrying arch 6, formed by the channel-bars 5 upon the axle-arch of the main frame. It will be understood that within the scope of the present invention the side members 11 of the frame F may be grooved or channeled, in which event the special guides or channel-bars 39 will be dispensed with.

Securely mounted upon the side members 11 of the frame F are supporting-blocks 40, having inclined faces 41, adjacent to which are mounted inclined guide members 42, which extend upwardly and rearwardly, the rear ends of said guide members being provided with upwardly and forwardly curved hook-

shaped members 43, which are approximately concentric with the axes of the supporting-pulleys 16, the points or extremities of said hook-shaped members being extended above the rear terminal of the track member 33. 70

Pivottally mounted upon the spindles 3 of the main axle are independent runner-frames 44, which are bifurcated to straddle the carrying-wheels 4 of the machine. The front ends of the runner-frames are equipped with rotary colters 45 and with runners or furrow-openers 46, seed-tubes 47, and boxes or hoppers 48, of ordinary construction, said boxes containing seed-dropping mechanisms, (not shown,) which are adapted to be actuated by 80 means of rock-shafts 49, which latter are suitably connected, as by means of universal joints 50, with rock-shafts 51, supported in the frame of the machine. The rock-shafts 51 are provided with upstanding arms 52, the latter being connected by tension-springs 53 with fixed points, such as the bracket members 7 of the main frame. An auxiliary frame 54 is supported upon each of the bracket members 7, and said frames are provided with 90 bearings for vertically-disposed rock-shafts 55, provided near their lower ends with lateral arms or tappets 56, extended inwardly in the path of the stakes 20. The rock-shafts 55 are also provided with arms 57, from which flexible members 58, such as wire cords, are guided over suitably-disposed pulleys or guiding members 59 to the upstanding arm 52 of the rock-shaft 51. It will be seen that when the rock-shafts 55 are oscillated by contact of 100 the tappet-arms 56 with one of the stakes 20 the oscillatory movement will be transmitted to the rock-shafts 51, which latter will be rocked in their bearings against the tension of the springs 53 until the tappet-arms pass 105 out of contact with the stake, when the spring 53 will automatically restore the rock-shafts 51 and 55 and related parts to normal position.

The chain-carrying frame F and all its related parts is supported adjustably with relation to the axle-arch of the main frame by a flexible connection extending from the arch member 6, as best seen at 60 in Fig. 5 of the drawings, to a suitably-constructed windlass 61, supported upon the axle-arch. 115

Supported upon the frame members 11 in rear of the axle and convenient to the driver's seat are obliquely-disposed bracket members including vertically-slotted uprights 62 and a laterally-extending arm 63, having a notch 64. Slidably engaging the slots 65 in the uprights 62 is a slide member 66. A sleeve 67, preferably square in cross-section, extends between the uprights 62 and is provided with a plurality of transverse slots or notches 68, 125 adapted to be engaged by the slide 66, which constitutes a locking member. Each of the sleeves 67 is provided at its rear end with a handle 69, and in the front end of each sleeve 130 is inserted a spring 70, having a stud 71 ex-

tending laterally through a slot 72 in the sleeve, within which the said spring is thus capable of partial rotation. The lower forward extremities of the springs 70 are suitably connected with the front ends of the runner-frames, the tendency of said springs being to retain said runner-frames in proper position with relation to the ground.

Suitably-supported levers 72^a are provided in rear of their fulcra with foot-pieces or treadles 73 in convenient reach of the driver or operator. The front ends of said foot-levers are connected with the runner-frames near the front ends of the latter. It will be seen that by depressing the rear ends of said foot-levers the front ends of the runner-frame may be elevated against the tension of the springs 70, thus enabling obstructions to be cleared by said runners independently of each other. The runner-frames may be sustained in an elevated position by moving the sleeves 67 of the springs 70 rearwardly between the slotted arms 62 and supporting the same at any desired adjustment by means of a slide or locking member 66.

Suitably-constructed drag and cross-row markers, as 75, are hingedly connected with the runner-frames, and the outer free ends of said markers may be retained at various adjustments by flexible members 76, suitably connected therewith and having knots or buttons 77 adjustable in the notches 64 of the arms 63.

From the foregoing description, taken in connection with the drawings hereto annexed, the operation and advantages of this invention will be readily understood by those skilled in the art to which it appertains. By manipulating the windlass 61 the chain-carrying frame F may be adjusted vertically, thus enabling said frame to be moved upward to an inoperative position, or it may be lowered so as to cause the stakes carried by the chain to enter into the ground to any desired depth. It will be observed that when the frame F is in its operative position the entire weight of said frame will be imposed upon the ground-engaging stakes. The latter may be adjusted in the casings of the special links 19 at various distances apart, according to the frequency with which it shall be desired to actuate the seed-dropping mechanism. Thus if it is desired to plant corn in hills three feet apart the stakes will be mounted in links exactly three feet apart, and it is desired to be understood that the chain-carrying frame is to be of such dimensions that not less than two stakes shall at all times be in engagement with the ground in order that certainty of operation may be insured. As the machine progresses over the ground the stakes which are in engagement with the ground will retain the lower lead of the chain in a relatively stationary position. When the machine in its progress reaches a point at which

the rear end of the chain-carrying frame approaches the rearmost stake, which is in engagement with the ground, the inclined guide members 42 will pass under the rollers 26 at the head of such stake, which will be removed from the ground by a straight upward pull exercised by the rollers 26, riding upon the guide members 41. When the stake has been drawn, it will be supported upon the approximately horizontal portions 42 of the guide members 41, and when the chain-link with which the stake is connected passes between the rear pulleys 16 the stake will be guided by the hook member 43 onto the upper portion 33 of the track 32. After traversing said track portion the laterally-extending ends of the shaft 27 will pass under the guide-flanges 37, and the stake will be guided over the front end of the track 32 while the chain passes between the front pulleys 16 until the stake is again inverted and resumes an approximately upright position, when by contact with the inclined portion 35 of the track member 34 it will be forced into the ground, the guide-flange 37 serving to prevent the stake from engaging the ground ahead of time by reason of gravity. The lower track member 34 engages the pulley 28 at the head of the stake, which latter is thus retained securely in the ground without danger of lateral displacement. As the machine progresses the tappet-arms 56 are actuated by the successive stakes, and the seed-dropping mechanism will thus be operated at regular predetermined intervals.

It will be seen that the stakes of this machine being positively spaced at certain distances apart and engaging the ground at right angles the seed-dropping mechanism will be actuated exactly at the proper intervals and with great accuracy.

In Figs. 3 and 4 of the drawings the links 18' of the chain 18, which are intermediate the special links 19, have been shown as being provided like, said special links, with laterally-extending arms, (here designated 23',) adapted to bear upon the peripheries of the pulleys 16 in order to prevent the chain from sagging or sinking between the pairs of said pulleys. This construction will usually be preferred and is considered to be within the scope of the invention.

Having thus described the invention, what is claimed is—

1. In a check-row corn-planter, a wheel-supported main frame including an arched axle, a chain-carrying frame having a supporting member guided in the axle-arch, an endless chain supported in said frame, and ground-engaging stakes bodily movable in links of said chain.

2. A main frame including an arched axle, channel-bars upon the side members of said axle, a supporting member guided for vertical movement in said channel-bars, a frame con-

nected pivotally with said supporting member, an endless chain supported in said frame, and ground-engaging stakes bodily movable in links of said chain.

5 3. A wheel-supported main frame, a supporting member guided for vertical movement in said frame, a chain-carrying frame connected pivotally with said supporting member, an endless chain, stakes bodily movable in links of said chain, and a stake-engaging track supported between the upper and lower leads of the endless chain.

10 4. A pivotally-supported frame including side members and arches spacing and connecting the same, pairs of pulleys supported for rotation at the ends of said frame, a chain extending between the pairs of pulleys and including links having arms peripherally engaging the latter and stakes movably connected 15 with said links.

15 5. In a check-row planter, a pivotally-supported frame including side members and arches spacing and connecting the same, pairs of pulleys supported for rotation at the ends 20 of the frame, a chain extending between the pairs of pulleys and including links having arms peripherally engaging the latter, and guides for said arms upon the inner sides of 25 the side members of the frame.

30 6. In a check-row planter, a frame including side members and arches spacing and connecting the same, pairs of pulleys supported for rotation at the ends of the frame, a chain extending between the pairs of pulleys and 35 including links having arms peripherally engaging the latter, guides upon the side members of the frame engaging said arms, and earth-engaging stakes slidably supported in the chain-links.

40 7. In a check-row planter, an endless chain supported for vertical adjustment, ground-engaging stakes slidably supported in links of said chain, and a guide-track for said stakes supported between the leads of the chain.

45 8. In a check-row planter, an endless chain supported for vertical adjustment, ground-engaging stakes slidably supported in links of said chain, and means supported between the leads of the chain for depressing the stakes 50 into the ground.

55 9. In a check-row planter, an endless chain supported for vertical adjustment, ground-engaging stakes slidably supported in links of said chain, and means supported between the leads of the chain for extracting the stakes from the ground.

60 10. In a check-row planter, an endless chain supported for vertical adjustment, ground-engaging stakes slidably supported in links of said chain, and means for engaging the stakes which are in ground-engaging position to retain said stakes in such position or against upward displacement.

65 11. In a check-row planter, an endless chain supported for vertical adjustment, ground-

engaging stakes slidably supported in links of said chain, a track supported between the leads of the chain and having an upper and a lower member connected at their front ends, a guide-flange upon the front end of said track, and 70 flange-engaging means upon the stakes.

12. In a check-row planter, an endless chain supported for vertical adjustment, ground-engaging stakes slidably supported in links of said chain, and means supported between the 75 leads of the latter for positively driving said stakes into the ground and for positively extracting the stakes.

13. In a check-row planter, a frame supported for vertical adjustment, an endless 80 chain supported in said frame, ground-engaging stakes connected slidably with links of said chain, and a stake-engaging track adjustably connected with the frame.

14. In a check-row planter, a frame supported for vertical adjustment, an endless chain supported in said frame, ground-engaging stakes connected slidably with links of 85 said chain, a stake-engaging track connected with the frame, and stake-extracting guides 90 supported upon the frame.

15. In a check-row planter, a frame supported for vertical adjustment, an endless chain supported in said frame, ground-engaging stakes connected slidably with links of 95 said chain, a stake-engaging track connected with the frame, and stake-extracting guides supported upon the frame; said guides being provided at their rear ends with forwardly-extending hook-shaped members for guiding 100 the stakes from the lower onto the upper portion of the track.

16. In a check-row planter, an endless chain supported for vertical adjustment, ground-engaging stakes slidably supported in links of 105 said chain, a guide-track for said stakes supported between the leads of the chain and comprising a lower and an upper member, and stake-extracting guides whereby said stakes will be guided from the lower onto the upper 110 member of the track.

17. In a check-row planter, an endless chain, chain-links having guiding-sleeves, ground-engaging stakes movable in said sleeves, guide-rollers upon the sides of said stakes, 115 and inclined guiding means adapted for engagement with said rollers to extract the stakes from the ground.

18. In a check-row planter, an endless chain supported for vertical adjustment, ground-engaging stakes slidably connected with links of 120 said chain, a wheel-supported carrying-frame, runners connected with said frame and having seed-dropping mechanism, rock-shafts connected with said frame and having 125 tappet-arms extended into the path of the ground-engaging stakes, and means for transmitting motion from said rock-shafts to the seed-dropping mechanism.

19. In a check-row planter, a wheel-sup-

ported main frame, a plurality of runner-frames pivoted independently upon said main frame, brackets supported upon the main frame, sleeves adjustable in said brackets, 5 springs movably connected with said sleeves and with the runner-frames to retain the latter in adjusted position.

20. In a check-row planter, a wheel-supported main frame, a plurality of runner-frames pivoted independently in said main frame, brackets supported upon the latter, sleeves adjustable in said brackets, springs movably connected with said sleeves and with the runner-frames, and foot-levers connected 15 with the runner-frames for adjusting the latter against the tension of the springs.

21. In a check-row planter, a wheel-supported main frame, a plurality of runner-frames pivoted independently in said main 20 frame, adjusting means for said runner-frames including tension-springs, and lever means for independently adjusting said frames against the tension of the springs.

22. In a check-row planter, a wheel-sup-

ported main frame, a chain-carrying frame 25 supported for vertical adjustment in said main frame, an endless chain, ground-engaging stakes movably connected with links of said chain, stake guiding, driving and extracting means connected with the chain-carrying 30 frame, runners connected with the main frame, spring-actuated rock-shafts connected with said runner-frames to actuate the seed-dropping mechanism, rock-shafts supported in the main frame and having tappet-arms extending 35 into the path of the ground-engaging stakes, and means for transmitting motion from the latter rock-shafts to the spring-actuated rock-shafts to move the latter against the tension of their actuating-springs. 40

In testimony that I claim the foregoing as my own I have hereto affixed my signature in the presence of two witnesses.

HENRY F. SPAULDING.
